UNITED STATES PATENT OFFICE.

HENRY J. COOPER, OF MOUNT VERNON, INDIANA.

FENCE-POST.

SPECIFICATION forming part of Letters Patent No. 743,150, dated November 3, 1903.

Application filed January 31, 1903. Serial No. 141,357. (No model.)

To all whom it may concern:

Be it known that I, HENRY J. COOPER, a citizen of the United States, residing at Mount Vernon, in the county of Posey and State of 5 Indiana, have invented a new and useful Fence-Post, of which the following is a specification.

My invention is an improvement in fence-posts and anchors for same; and the object 10 of my device is to provide a simple and efficient method of securely anchoring the post without the use of side braces, brackets, &c.

It will be understood that while my improved anchor is shown and described in connection with a post, yet it can readily be applied to telegraph and other poles or to beams of any kind which it is desired to implant vertically in the earth.

In the accompanying drawings, Figure 1 is 20 a perspective view of my post and anchor in position. Fig. 2 is a view of the post in elevation. Fig. 3 is a cross-section through the post about on the line 3 3 of Fig. 2. Fig. 4 is a perspective view of my post and anchor, 25 showing a form of brace. Fig. 5 is a detail view of the bottom plate. Figs. 6, 7, 8 are detail views of various forms of braces used with my bottom plate.

In carrying out my invention I employ, 30 preferably, a post comprising four laterally-projecting wings A, each having a vertical series of perforations A' corresponding in number to the strands of wire of which the fence is to be composed. Adjacent its lower 35 end the post may be either square or circular in shape and terminates in a reduced circular threaded shank A². I also employ a bottom plate having a central socket B and four laterally-extending wings B' B² B³ B⁴, 40 spaced an equal distance apart. The wing B³ is sharpened at its outer end, and the wings B² B⁴ have their sides adjacent the wings B³ sharpened to form cutting-plates. The socket B is interiorly threaded to receive 45 the shank of the post.

The first anchor-brace comprises a boxing C, longitudinally slotted, the slots intersecting centrally at right angles, as shown at C', and the boxing C is adapted to slide on the 50 post. The boxing carries the flat horizontal integral top plates C², at each end of which are the downwardly-extending end pieces C³,

having the cutting-blades C⁴ at their lower ends and the cross-strip C⁵ connecting the end strips, the cross-strip having the cutting edge 55 C⁶ formed thereon.

In Fig. 7 a slightly-modified form of brace is shown, the boxing D corresponding to the C of Fig. 8. It is slotted at D', being also adapted to slide over the post, and has connected to one side a strip D², corresponding to C⁵, extending an equal distance on opposite sides of the boxing and having a flange D³ along the upper edge. At each end of this strip are the end pieces D⁴, arranged 60 transversely to the strip D² and extending below the lower edge of same, and the lower edges of the strips D⁴ are beveled, as at D⁵. It will be obvious from the drawings that if C² of Fig. 8 was cut away on each side and 65 C⁵ raised to a higher position the form shown in Fig. 7 would practically be produced.

In Fig. 6 I have shown the boxing E similar to and slotted like C and D.

Intersecting wings E' are secured to adjacent sides of the boxing and have their lower edges, which are below the plane of the boxing, sharpened.

The mode of using my device is as follows: A hole large enough in diameter to permit 80 the bottom plate to be inserted horizontally therein is dug one foot from the fence-post line and of a depth equal to the depth of the post-hole. The shank of the post is screwed into the socket B and the plate lowered into 85 the hole, with the wing B³ pointing toward the fence-line. The post is then withdrawn and a hole bored with a post-auger on the fence-line and to the same depth as the first hole. The winged bottom plate is then forced 90 through the ground between the two holes, the cutting edges of the wings rendering this possible, and when the socket B is in alignment with the bored post-hole the shank A² will fall into same, the post having been 95 inserted in the post-hole either before or after the forcing of the bottom plate, and the post is turned, threading the shank into the socket. The boxing C, D, or E is then slipped on the post and driven down into the ground, 100 the blades C³, D⁴, or E', as the case may be, are forced downward into the ground, firmly bracing the post. The boxings are similar, and each have blades or wings having sharp-

ened lower edges, the blades secured differently to the boxes, and are thereby adapted for use in different soils, the form shown in Fig. 6 being especially adapted for use in hard ground, while the form shown in Fig. 8 is more effective in swampy ground.

It is understood that the anchor parts are of metal and that the wings are cast integral with the boxing to which they are connected.

10. The posts may be either metal or wood. The wires are connected to the posts by short wires passed through the perforations, passed over and under the fence-wire, and twisted.

Having thus fully described my invention, 15 what I claim as new, and desire to secure by Letters Patent, is—

1. The combination with a fence-post, of a flat bottom plate having four flat lateral wings one of said wings being sharpened at one end, and the two adjacent wings being sharpened 20 on one edge.

2. The combination with a fence-post, a bottom plate, having a plurality of wings with cutting edges and a socket receiving the lower end of the post, and an anchor member having a boxing adapted to slide on the post and having lateral wings sharpened on their lower edges. 25

HENRY J. COOPER.
